JAMES P. JACKSON, OF CHICAGO, ILLINOIS, ASSIGNOR TO ADDRESSOGRAPH COMPANY, OF WILMINGTON, DELAWARE, A CORPORATION OF DELAWARE

PRINTING DEVICE

Original application filed October 17, 1930, Serial No. 489,278. Divided and this application filed January 2, 1932. Serial No. 584,381.

This is a division of my application Serial No. 489,278, filed October 17, 1930.

The invention relates to printing devices and more particularly to one-piece sheet metal printing devices on which printing characters are embossed to appear in relief on one face and in intaglio on the opposite face. Such printing devices are classified, usually alphabetically, and are stored in drawers when not in use, and in use they are sequentially fed through printing machines to print addresses and the like.

Printing devices of this kind are arranged in close relation when stored and spacing flanges are provided thereon to space the faces of adjacent printing devices from each other to prevent damage of the printing characters. In arranging the printing devices in this close relation they are slid one over the other and sometimes the free edges of the spacing flanges on one device are engaged by edges or corners of the printing devices being slid thereover. This is disadvantageous since the spacing flanges may be damaged and proper nesting and alignment of the printing devices be impaired. It is therefore one of the objects of my invention to provide a novel printing device wherein the spacing flanges are protected so that the likelihood of damage thereto in handling and arranging of the printing devices will be obviated.

To keep the size of the spacing flanges at a minimum the relief or front face of the printing device is often in the nature of a depressed panel having a raised border therearound usually provided by offsetting the marginal edges of the printing device upwardly on the relief face and, when the printing devices are compactly arranged, spacing flanges on one printing device engage the raised border on the adjacent printing device to thereby amply space the printing characters on one printing device from the other printing device to prevent damage thereto. To offset the marginal edges of the printing device upwardly on the relief face entails an additional operation in the manufacture of the printing devices and an object of my invention is to provide a printing device wherein the relief face is in the nature

of a depressed panel defined by bending the marginal edges of the printing device onto the relief face thereof.

Further objects of the invention are to provide a printing device which may be expeditiously and economically manufactured as by being passed through a rolling machine, and which is sturdy in construction so as to resist bending and other distortion thereof in use.

A selected embodiment of the invention is illustrated in the accompanying drawing and therein.

Fig. 1 is an elevation of the blank from which my novel printing device is formed;

Fig. 2 is an elevation of the relief face of the completed printing device;

Fig. 3 is a longitudinal sectional view taken substantially on the line 3—3 on Fig. 2;

Fig. 4 is a transverse sectional view taken substantially on the line 4—4 on Fig. 2.

In the drawing, 5 is the body of my novel printing device, the rectangular blank for which is struck from suitable sheet metal.

The corners of the blank are cut away to define projecting relatively narrow edge sections 6 and 7 along the longer edges of the blank and to provide projecting relatively wide edge sections 8 and 9 along the narrower edges of the blank. The edge sections 6 and 7 are folded over onto one face of the body 5 to lie flatly thereon whereby rounded edges 9' and 10 are formed along the longer edges of the body. As best illustrated in Fig. 3, the edge sections 8 and 9 are first angularly bent outwardly from the face of the body opposite that onto which the edge sections 6 and 7 are folded and then these sections are angularly bent to extend toward the plane of the body whereby substantially triangularly shaped spacing flanges 11 and 12 are formed and the free marginal edge portions 13 and 14 are folded inwardly over the open bases of the triangular spacing flanges 11 and 12. The free edges of the portions 13 and 14 abut the ends of the edge sections 6 and 7 to thereby provide a depressed panel. By so folding the portions 13 and 14 rounded edges 15 and 16 are formed along the shorter edges of the

body. The edge sections may be conveniently made by passing the blanks through a suitable rolling machine having appropriately shaped rollers to fold the edges in the manner 5 above described. The printing characters 17 are embossed on the body of the blank to appear in relief on the face thereof having the edge portions 6, 13, 7 and 14 folded thereonto. When such printing devices are arranged in 10 side by side relation, the apices of the triangular spacing flanges 11 and 12 rest on the edge portions 13 and 14 which provide abutment or seating surfaces and therefore the bodies of the printing devices are amply spaced apart 15 to thereby prevent damage to the printing characters. Since the edges of the printing device are rounded by reason of the folding of the marginal sections onto a face of the body, the printing device is free of sharp 20 edges and therefore the printing devices will freely slide one over the other. Since the spacing flanges are defined by continuously bent sections and as the marginal portions of the sections providing the spacing flanges lie 25 on the relief face of the printing device and abut against the ends of the marginal portions folded onto the relief face of the printing device, damage to the spacing flanges is effectively prevented for the sections 6 and 7 30 serve to prevent an edge of another printing device engaging the free edges of the spacing flanges. Furthermore, by folding the free marginal sections onto one face of the printing device a depressed panel is defined and 35 when the printing characters are embossed to appear in relief in this depressed panel, the printing faces thereof will project but slightly beyond the sections bent onto the relief face and since the spacing flanges on the adjacent printing device will be engaging the 40 abutment surfaces 13 and 14 the bodies of the adjacent printing devices will be amply spaced apart and consequently contact with and resulting damage to the printing faces 45 of the printing characters is prevented.

In the foregoing description I have set forth a selected embodiment of my invention but it is to be understood that this is susceptible of variation and modification and I therefore do not wish to be limited to the precise details set forth but desire to avail myself of such changes and alterations as fall within the purview of the following claims.

I claim:

- 55 1. A printing device having marginal sections along opposite edges thereof and folded onto one face thereof, said device having other marginal sections along other opposite edges thereof folded to provide abutment 60 surfaces, the edges of the last-named marginal sections engaging the ends of said first-named marginal sections, all of said marginal sections providing a raised border on one face of said printing device.
- 65 2. A printing device including a body hav-

ing marginal sections along opposite edges folded onto one face thereof, said body having other marginal sections along other marginal edges thereof providing abutment surfaces on said face, said marginal sections providing a raised border about the edges of said body on said face.

3. A printing device including a body having opposite marginal sections thereof folded to provide marginal borders on one face and along opposite edges thereof, said marginal sections being terminated inwardly of other opposite edges of the body, said body having the marginal sections along said other edges folded to provide abutment surfaces and having the adjacent edges of said sections providing said abutment surfaces engaged with the ends of said marginal borders to thereby provide a raised marginal border about the edges of said body on said face, said body having printing characters embossed thereon with the relief faces thereof on said face of said body.

4. A printing device including a body having marginal sections along opposite edges and folded onto one face thereof, said body having other marginal sections along other marginal edges thereof and folded to provide abutment surfaces on said face, said folded marginal sections providing a raised marginal border about the edges of said body on said face, and spacing flanges on the opposite face of said body.

5. A printing device including a body having marginal sections along opposite edges folded onto one face thereof, said body having other marginal sections along other marginal edges thereof folded to provide abutment surfaces on said face, said folded marginal sections providing a raised marginal border about the edges of said body on said face, and spacing flanges on the opposite face of said body, said spacing flanges being aligned with and disposed opposite said abutment surfaces.

6. A printing device including a body having marginal sections along opposite edges and folded onto one face thereof, and said body having other marginal sections along other marginal edges thereof folded onto said face to provide abutment surfaces, the portions of said marginal sections providing said abutment surfaces and inwardly of said abutment surfaces being bent at angles to said body to provide spacing flanges opposite said abutment surfaces.

7. A printing device including a body having opposite marginal sections folded onto one face to provide marginal borders along opposite edges thereof, said body having the marginal sections along other opposite edges thereof first bent away from said body and then bent toward said body to provide spacing flanges on the face of said body opposite the face having said marginal borders there-

on, and abutment surfaces on said face having said marginal borders thereon.

8. A printing device including a body having opposite marginal sections thereof folded 5 onto one face thereof to provide a raised marginal border along opposite edges thereof, said marginal borders being terminated inwardly of the other edges of said body, said body having the marginal sections along said 10 other edges first bent away from said body and then bent toward said body to provide substantially triangular spacing flanges on the face of said body opposite that on which said marginal borders are formed, the free 15 marginal portions of said marginal sections providing said spacing flanges being folded onto said face and into engagement with the ends of said marginal borders to provide abutment surfaces and cooperating 20 with said marginal borders to provide a raised marginal border about the edges of said body on said face.

9. A printing device including a body having opposite marginal sections thereof folded 25 to provide marginal borders on one face and along opposite edges thereof, said body having marginal sections along other edges thereof first bent away from said body and then toward said body to provide substantially triangular spacing flanges on the 30 face of said body opposite that having said marginal borders thereon, the free marginal portions of said marginal sections providing said spacing flanges being folded to overlie 35 the open bases of said triangular spacing flanges and to extend in the plane of said marginal borders to cooperate with said marginal borders to provide a raised marginal border about the edges of said body on said 40 face, said body having printing characters embossed thereon with the relief faces thereof on said face.
